UNITED STATES PATENT OFFICE

GEORGE F. YAGER, OF TOLEDO, OHIO, ASSIGNOR TO THE BUNTING BRASS AND BRONZE COMPANY, OF TOLEDO, OHIO, A CORPORATION OF OHIO

STAMPING MACHINE

Application filed March 10, 1930. Serial No. 434,800.

This invention relates generally to stamping machines, particularly to those designed for stamping indicia such as "Bunting. Made in U. S. A.", upon tubular objects, such as bushings, and consists of certain novel features of construction, combinations and arrangements of parts that will be herein-after more fully described and particularly pointed out in the appended claims.

10 In the accompanying drawings:

Figure 1 is a top plan view of a machine embodying my invention;

15 Figure 2 is a front elevation with parts broken away and in section of the machine illustrated in Figure 1;

Figure 3 is an end elevation of the machine;

Figure 4 is another end elevation of the machine;

20 Figure 5 is a sectional view taken on the line A--A of Figure 2.

Referring now to the drawings, 1, 2, 3 and 4 respectively are upright walls, and 5 is the top wall of the machine casing; 6 is an electric motor mounted upon the wall 4 and having a relatively short shaft 7; 8 is a stub shaft journaled in a bearing 9 projecting inwardly from the wall 3 in a plane substantially parallel with the shaft 7; 10 and 11 respectively are pulleys keyed upon the shafts 7 and 8 at the outer ends thereof; and 12 is a belt connecting said pulleys 10 and 11.

25 13 is a drive shaft journaled in the upright walls 2 and 3 adjacent the lower ends thereof; 14 is a gear keyed upon the shaft 13; 15 is a pinion on the shaft 8 meshing with the gear 14; 16 is a clutch collar controlling the driving connection between the pinion 15 and gear 14; 16' is a clutch operating shaft; 40 and 16'' is an operating lever for the shaft 16'. 17 is a cam shaft journaled in the upright walls 2 and 3 above the drive shaft 13; 18 and 19 respectively are pulleys keyed upon the shafts 13 and 17; and 20 is a belt connecting the pulleys 18 and 19.

45 21 is a stamp arbor journaled in a rocker 22 and connected by the gears 23, 24, shaft 25 and gears 26, 27 and 28 respectively to the cam shaft 17 so that the arbor rotates whenever the cam shaft is rotating. Preferably

the rocker 22 is substantially T-shaped and is mounted to rock upon the shaft 25 projecting laterally from an upright wall 29 of an upwardly opening substantially U-shaped depression 30 in the top wall 5 of the casing. 55 As shown, the wing portions 31 and 31' of the rocker have elongated slots 32 and 33 therein that receive the shanks of suitable securing bolts 34 and 35. 36 is a stamp non-rotatably sleeved upon the arbor 21 and having a die 37 to produce the desired indicia upon the bushing. 38, 39 and 40 respectively are spacers sleeved upon the arbor 21 for positioning the stamp 36 at the proper point longitudinally of the arbor for the proper engagement thereof with the work; 41 is a retaining nut sleeved upon the arbor; and 42 is a bracket detachably secured in a rabbet 43 in the outer face of the rocker 22 and having a bearing portion 44 for the reduced end portion 45 of the arbor. Normally this bracket 42 is secured to the rocker and serves as a support for the outer end of the arbor, however, the bracket may be readily removed by removing the securing bolts 46 from the 75 rocker to permit stamps such as 36 to be placed on or removed from the stamp arbor 21.

47 and 48 respectively are channel sections of a chute for conducting bushings and the like beneath the stamp arbor 21 and thence through the walls 1 and 4 to a suitable receptacle such as 49 upon a roller conveyor 50. As shown, the upper section 47 of the chute is straight and received in and supported by the channel-shaped portion 51 of a bracket 52 adjustable vertically upon the wall 4 of the machine frame. As illustrated in Figures 3 and 5, the upright portion 53 of the bracket has an elongated slot 54 that receives the shank of a bolt 55 carried by the wall 4 and preferably rests upon the head 56 of a vertical bolt 57 adjustable vertically in a block 58 bolted to and constituting a lateral projection of the wall 4. The lower section 48 has a substantially U-shaped portion 59 constituting an extension of the lower end of the upper section 47 and supported upon vertically adjustable brackets 61 and 62 respectively upon the front wall 1 of the machine, 100

and has a straight portion 63 parallel to the upper section 47. Thus the chute is substantially U-shaped in plan.

64 is a stop for the bushings traveling down the chute section 47, 65 is a supporting bracket for the stop, 66 is a cam lever for raising and lowering the stop relative to the chute, and 67 is a cam for raising and lowering the free end of the lever 66. As shown, 10 the stop 64 extends transversely of the chute, preferably above and at one side thereof, and has a relatively long cylindrical stem 68 that is adjustable longitudinally within a clamp 69 upon a shaft 70 journaled in laterally 15 spaced bearings 71 and 72 of the bracket 65. The lever 66 is secured by a suitable pin to the shaft 70 at one end thereof and rests upon the cam 67. Preferably the cam 67 is upon the outer face of the gear 26 keyed upon the 20 shaft 25 whereby rotation of the shaft and gear will cause the lever 66 to move upwardly and downwardly so that the stop 64 will be raised and lowered relative to the chute. In this connection it will be noted that the bushings 25 received in the chute travel upon a booster belt 73 trained about rollers 74 and 75 respectively. As shown, the roller 75 constitutes an idler roller and is free to rotate upon the shank 76 of a bolt 76' that serves as a tie 30 or connection between the side walls of the chute sections 47 and 48. The roller 74 constitutes the driving roller for the belt and is rigid with a shaft 77 received in elongated slots 78 in opposite sides of the channel portion 51 of the bracket 52. A shaft 78' is journaled in a bearing 79 constituting a lateral projection of the wall 4 and is operatively connected by the universals 80 and 81 and intermediate shaft 82 to the shaft 77. Preferably the shaft 78 is driven from the drive 35 shaft 13 and for this purpose pulleys 83 and 84 are keyed upon the respective shafts 78 and 13 and are connected by a suitable belt 85.

86 is a plunger movable within a bushing when the latter is in a position to be engaged by the stamp die 37, 87 is a support for the plunger during the stamping operation, 88 is a reciprocating holder for the plunger 86, 89' is a bearing for the holder 88, 89 is a block 40 secured within the holder 88, 90 is a block secured in a recess in the block 89 and projecting laterally through an elongated slot 91 in the holder 88, 92 is a roller carried by a pin 93 projecting from the blocks 89 and 90, 45 and 94 is a cam on the shaft 17 having a cam slot 95 receiving the roller 92 and adapted to cause the plunger holder 88 to reciprocate in the bearing 89'. As shown, the plunger 86 is received within a socket 96 held by set screw 97 within the holder 88, and is provided with a conical free end 98 that is receivable within a U-shaped recess or groove 99 in the work holder 87. This holder 87 is secured by the bolts 100 and screws 101 to an upstanding 50 flange 102 of the depression 30 in the top

wall 5. Preferably the bearing 89' for the reciprocating plunger holder is supported at its opposite ends in an enlargement 103 of the upright wall 104 of the depression 30 and in a bracket 105 bolted to the wall 2. A tubular casing 106 is secured by suitable screws 107 to the bracket 105 in line with the bearing 89' at the outer end thereof for receiving the outer end of the plunger holder 75 when the latter is in its outermost position.

In use when the machine is initially started, a bushing is placed on the booster belt 73 in the chute section 47 against the stop 64 whereupon bushings to be stamped are fed onto the booster belt 73 at the upper end of the chute section 47. The bushings will move down the chute with the booster belt 73 and will successively receive the plunger 86 and thereafter will successively engage the stop 64. While on the plunger, the bushing is stamped by the die 37 of the stamp on the arbor 21. In this connection it will be noted that the plunger actuated by the cam 94 moves forward into a bushing, onto the plunger support 87, and remains stationary while the stamp 36 revolves and stamps the bushing. The stop 64 actuated by the cam 67 then raises and permits the bushing formerly in engagement therewith to pass downwardly in the chute section 59 into the receptacle 49 and then returns to lowered position. The plunger 86 is then withdrawn by the cam from the bushing just stamped and allows the said stamped bushing to advance into engagement with the stop, permitting the next bushing in line to receive the plunger on its return stroke to the plunger support 87. This cycle of operation is repeated as long as the machine is running.

Thus from the foregoing it will be apparent that stamps such as 36 having dies of various configurations and designs may be employed and that a number of such stamps may be mounted side by side or in spaced relation on the arbor 21 for stamping the bushings or similar articles. The booster belt 73 keeps the bushings moving down the chute, and the stop 64 engages the bushings as they are stamped and this causes the next bushing to be in line with the plunger 86 to receive the same preliminary to being engaged by the die of the stamp on the arbor. The arbor rotates constantly, and the adjustment provided for the rocker 22 carrying the arbor is such that adjustments may be made to compensate for bushings having different wall thicknesses or for plungers having larger or smaller diameters.

While it is believed that from the foregoing description the nature and advantages of the invention will be readily apparent, I desire to have it understood that I do not limit myself to what is herein shown and described, and that such changes may be re-

sorted to when desired as fall within the scope of what is claimed.

What I claim as my invention is:

1. In a stamping machine, a rotatable stamp arbor, means for conducting the work adjacent the arbor, a stop for the work adjacent the conducting means, a driven shaft, a driving connection between the shaft and arbor, means associated with said driving connection for actuating said stop, and means independent of said driving connection establishing a driving connection between said shaft and conducting means. 70
2. In a stamping machine, a stamp arbor, means including a chute and a booster belt movable longitudinally of said chute for conducting work adjacent the arbor, a driven shaft, a driving connection between said shaft and arbor, and a driving connection between said shaft and booster belt. 75
3. In a stamping machine, a stamp arbor, a driven shaft, a driving connection between said shaft and arbor including a cam shaft, means for conducting work adjacent the arbor, means engageable with the work when adjacent the arbor to retain the same in position to be stamped, a driving connection between said retaining means and cam shaft, and means independent of said cam shaft establishing a driving connection between said driven shaft and conducting means. 80
4. In a stamping machine, a rotatable stamp arbor, a chute beneath the arbor, longitudinally movable means movable across the chute adjacent the arbor to engage and retain the work in a predetermined position relative to the arbor, a cam shaft, a cam on said shaft, a driving connection between said shaft and arbor, and means for translating motion from the cam to the longitudinally movable member. 85
5. In a stamping machine, a constantly rotating stamp arbor, a stamp carried by said arbor, means movable longitudinally in a plane at substantially right angles to the axis of the arbor for conducting work adjacent the arbor, and means movable in a plane substantially parallel with the axis of the arbor to retain work in a position to be engaged by said stamp. 90
6. In a stamping machine, a frame, a rocker adjustable on the frame, a bracket detachably mounted on the rocker, and a rotating stamp arbor having spaced portions thereof journaled in said rocker and bracket. 95
7. In a stamping machine, a frame having upright portions, and a chute substantially U-shaped in plan having a portion adjustably mounted on an upright portion of said frame and having another portion extending through an upright portion of the frame. 100
8. In a stamping machine, a frame having an upright portion, a chute, and a support for the chute including a longitudinally adjustable element substantially parallel with the upright portion of the frame, and a bracket slidably mounted on the upright portion of the frame as a follower of said element and having a portion slidably engaging the chute. 105
9. In a stamping machine, a chute having two sections, a bolt connecting said sections, an endless conveyor extending longitudinally of the chute, and a rotatable support for the conveyor mounted on said bolt. 110
10. In a stamping machine, a rotating stamp arbor, and supports for said arbor including members engaging opposite ends of the arbor, one of said members being removable from the arbor to permit stamps to be placed thereon or removed therefrom. 115
11. In a stamping machine, a driven shaft, a cam shaft driven from the driven shaft, a rotating stamp arbor, a driving connection between said arbor and cam shaft, means for feeding work to a point adjacent the stamp arbor, and a driving connection between said feeding means and driven shaft. 120
12. In a stamping machine, a cam shaft, a rotating stamp arbor, a driving connection from said shaft to said arbor, means for conducting work to a point adjacent the arbor, means for stopping the work when it is adjacent the arbor, and means associated with the driving connection between said shaft and arbor for controlling the movements of said stop means. 125
13. In a stamping machine, a cam shaft, a rotating stamp arbor, a driving connection between said shaft and arbor, means for conducting the work into a position to be stamped, means movable into engagement with the work when it is in said position to retain the same in said position while being stamped and movable out of engagement with the work to permit the same to leave said position after it is stamped, and actuating means for the last mentioned means including a cam on said shaft, and a reciprocating member actuated by said cam. 130
14. In a stamping machine, means for stamping the work, means for conducting the work into a position to be stamped, means for holding the work while it is stamped, and actuating means for said holding means including a rotating shaft, a cam on the shaft, and a reciprocating member actuatable by said cam. 135
15. In a stamping machine, a stamp arbor, means including a movable element for supporting the work adjacent the arbor, means including a rotatable element for conveying the work to the supporting means, a drive shaft, a shaft driven from the drive shaft, a connection between one of said shafts and the movable element, and a connection between the other of said shafts and the rotatable element. 140
16. In a stamping machine, a stamp arbor, means including a reciprocating element for 145

supporting the work adjacent the arbor, means including a rotatable element for conveying the work to the supporting means, a drive shaft, a shaft driven from the drive shaft, a connection between the driven shaft and the reciprocating element, and a connection between the drive shaft and the rotatable element.

17. In a stamping machine, a rotatable stamp arbor, a reciprocating work holder adjacent said arbor, a driven shaft, a connection between said shaft and rotatable arbor, a cam on the shaft, and a connection between said cam and reciprocating work holder.

18. In a stamping machine, a drive shaft, a driven shaft, a rotatable stamp arbor, a conveyor for conducting the work to the arbor, a connection between said drive and driven shafts, a connection between one of said shafts and said arbor, and a connection between the other of said shafts and the conveyor.

19. In a stamping machine, a rotatable shaft, a cam on the shaft, a rotatable stamp arbor, a driving connection between said arbor and shaft, means for holding the work adjacent the arbor, and a driving connection between said holding means and cam.

20. In a stamping machine, a rotatable shaft, a rotatable stamp arbor, a driving connection between said arbor and shaft, means for conducting the work to the arbor, and means operable by the connection aforesaid for stopping the work conducted by the last mentioned means when it reaches a predetermined point relative to the arbor.

In testimony whereof I affix my signature.
GEORGE F. YAGER.
